UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

HOPPER CAR.

Application filed July 20, 1923. Serial No. 652,733.

The accompanying drawings illustrate the preferred form of the invention, though it is to be understood that the invention is not limited to the exact details of construction shown and described, as it is obvious that various modifications thereof within the scope of the claims will occur to persons skilled in the art.

In said drawings:

10 Fig. 1 is a side elevation of a hopper car constructed in accordance with my invention, certain portions being broken away to show the door operating mechanism parts in assembled relation and mounted in service position;

15 Fig. 2 is a plan view of a portion of the car with certain parts broken away to more clearly show the application of the door operating mechanism;

20 Fig. 3 is a vertical sectional view taken on line 3—3 of Fig. 1, looking in the direction indicated by the arrows and showing the pawl, door operating, and crank shaft elements of the door mechanism, and portions of the end floor and side walls broken away to show the side wall assembly;

25 Fig. 4 is a vertical sectional view taken on line 4—4 of Fig. 3, looking in the direction indicated by the arrow and showing the crank shaft and door link connections;

30 Fig. 4^a is a sectional view taken on line 4^a—4^a of Fig. 4, looking in the direction indicated by the arrow and showing the crank frame and door link connection mounted upon the bearing bracket;

35 Fig. 5 is a vertical sectional view taken on line 5—5 of Fig. 2, looking in the direction indicated by the arrow and showing the stop lug of the crank shaft within the sprocket wheel; and

40 Figs. 6 to 11 inclusive represent the positions of the crank shafts at opposite ends of the doors, the sectional views corresponding to one on line 7—7 of Fig. 5, and show in Figs. 6 and 7 the relative positions of shaft lug and sprocket wheel just prior to the door unlocking movement, and in Figs. 8 and 9 the position of shaft after dropping of the doors, and Figs. 10 and 11 show the 45 relative positions of shaft and sprocket wheel when doors have been raised and shafts locked.

45 My invention relates to that class of hopper bottom cars used primarily in the ore carrying service and has for one of its ob-

jects the provision of door operating mechanism designed to drop the doors to discharge the lading and to raise and support them in closed position, such mechanism including suitable lost motion devices to permit the doors to drop without communicating such movement to the operating shaft.

50 In the drawings; 10 represents a car of the hopper type having a single discharge opening 11 in its bottom, the bottom being closed by a pair of doors 12 hinged at the car sides and meeting with their free edges at the longitudinal center of the car.

55 The discharge opening 11 is defined by the hopper side sheets 13 and the sloping end sheets 14. The doors extend the entire length of the door opening and are of sufficient strength to carry the load upon them, being provided with door stiffeners 15 along their free edges and braced by hinge members 16 secured to the doors transversely thereof. The hinge members 16 are pivoted at 17 to hinge brackets 18 secured to the inner longitudinal side sill members 19 of the car underframe 9. The doors are hung adjacent the hopper side sheets 13 which terminate in a plane above the edges of the sloping end sheets 14, permitting the doors to assume a contour substantially angular in cross section in order that the space between the edges of the sloping end sheets may be utilized for load carrying purposes.

60 The doors are provided at their ends with projecting portions 20, shown in the drawings as forming extensions of the door stiffeners 15, designed to afford attachment for the door links 21. The door links comprise the jaws 22 pivotally connected to the door projections 20 by pins 23, the yoke piece 24 mounted on pin 25 having a bearing in the 65 crank frame 26, and link rods 27 pivotally secured to the yoke piece 24 and pivotally and adjustably secured at their lower ends to the jaws 22. This arrangement permits free play of the door links throughout the full 70 range of door travel and crank frame movement.

75 The crank frame 26 comprises the arms 28 connected by a web 29 extending along one edge of said arms. The arms are provided with integral trunnion portions 30 journaled in a bearing bracket 31 designed to connect the sloping end floors 14 and draft members 32 of the underframe 9. The bearing bracket transmits the load on the crank 80

arms and sloping end floor directly to the underframe through the draft members 32, performing this function by virtue of the rivets 33 and 34 respectively, connecting the 5 end floor and draft members to the bracket.

The bearing bracket 31 is provided with a pair of inwardly extending trunnion bearings 35 open preferably at the upper sides 36 of such inwardly extending portions to 10 allow the passage downwardly of the trunnions 30 during the process of assembling said parts. The trunnion bearings are fitted with removable bushings 37 adapted to receive the trunnions 30 over their peripheries to provide positive means for holding the crank arm trunnions 30 to their bearings 35. Any tendency on the part of the trunnions to leave their bearings would be resisted by the inwardly projecting bushings 15 37 whose upper sides 38 extend above the trunnions. The bushings themselves are held down by the engagement of the trunnion bearings 35 with the inner ends of the upper side portions 38 of the bushings. The 20 bushings 37 are prevented from moving inwardly by the crank arms 28 with which the bushings will contact before they become disengaged from their bearings 35. The bushings are held from outward movement 25 at one side of the crank frame by means of stop plates 39 secured to the bracket 31 by bolts 40, or the like, and on the opposite side by a washer 41 secured by a cotter 42 to a crank shaft 43 of the crank frame operating mechanism hereinafter to be described.

When mounted with their trunnions journaled in brackets 31 underlying the sloping end floors 14 of the hopper, the crank frames 26 are in condition to be actuated by the operating mechanism to rotate about their bearings from their locked door supporting position shown in full lines in Fig. 4 to their released load discharging position shown in broken lines of that figure. In their door 45 supporting position the crank frames lie with their connecting web portions 29 against the upper marginal edge 44 of bracket 31. In this position the door links 21 lie in a plane passing through crank pin 25 and jaw pins 23 50 and inside of a plane through the axial center of the trunnions 30, tending thereby to induce rotation of the crank frames toward the hopper end floors 14 and locking them against reverse movement until forced outwardly beyond the dead center of the parts 55 whereupon such parts will move under the weight of the load to release the doors to discharge the lading.

The operating mechanism comprises a pair 60 of crank shafts 43 arranged transversely of the car and mounted adjacent the underside of the sloping end floors 14 and journaled at their outer ends in bearings 44^a secured to the outer longitudinal side sill members 65 45 and engaging at their inner ends with re-

spectively adjacent crank arm trunnions 30. The trunnions are formed with polygonal openings 48 to receive correspondingly shaped ends 48^a of the crank shafts 43. The crank shafts each engage but one trunnion of each of the crank frames, but both trunnions of the crank frames are provided with shaft openings to permit the use of identical crank frames at opposite ends of the doors. The crank shafts are further provided at their outer ends with lugs 49 designed to engage lugs 50 on driven sprockets 51 and 52 providing a loose connection between the crank shafts 43 and an operating shaft 53 to permit the dropping of the doors and rotation of the crank shafts 43 without communicating such movement to the operating shaft 53.

The driven sprockets are loosely fitted to the crank sheets 43 as shown in Fig. 5 and are formed to interlock with the shaft lugs 49 for limited rotation on the shaft and to prevent shifting thereof longitudinally of the shaft. The said sprockets are mounted in a plane adjacent the car side 90 and are connected together by a link belt mechanism 54 for the simultaneous operation of the crank frames 26 at opposite ends of the hopper, the link belt connection being so designed as to effect the relatively 95 opposite rotation of the crank shaft sprockets, crank shafts, and crank frames 26, respectively.

The link belt 54 is continuous and extends from the upper side of the driving sprocket 55 on the operating shaft 53 directly to the upper side of the crank shaft sprocket 52 at the opposite end of the hopper, thence about the periphery of said sprocket 52 to the underside thereof from which point the belt 105 returns in the direction of sprocket 51 to engage the upper side of said wheel thence to the underside of the driving sprocket 55 on the operating shaft 53. To insure positive engagement of belt and upper peripheral portion of sprocket 51 an idler 56 is employed to hold the belt to the sprocket. The idler 56 is secured to the underframe 9 by bracket 57 and lies above the lower strand of the continuous belt 54 as shown 110 in Fig. 1 and effectually guides the belt to the sprocket 51.

At points intermediate the guiding idler 56 and the lower peripheral side of sprocket 52, the lower strand of the link belt is supported upon rollers 58 journaled in brackets 59 secured to the car underframe 9, while the upper strand of the link belt is supported intermediate the sprockets 52 and 51 upon rollers 60 journaled in brackets 61 secured to the framing gusset braces 62 having openings 63 through which the belt passes. The link belt 54 is partially made up of connecting rods 64 in those portions thereof which play between the sprockets and is adjustably 125 130

mounted by means of the turnbuckles 65 connecting adjacent ends of rods 64 in both upper and lower portions of the belt.

The operating shaft 53 extends from side to side of the car and has fixed thereon the driving sprocket 55 adjacent to the crank shaft sprocket 51 and in position to engage the belt 54. Adjacent the driving sprocket 55 is fixed a ratchet wheel 66 designed to engage a locking pawl 67 fixed to the adjacent end of a pawl shaft 68 paralleling the operating shaft 53 and also extending from side to side of the car and operable from either side. The pawl 67 is actuated by a handle 69, preferably integral with the pawl and serving as a counterbalance to either hold said pawl in engagement with the ratchet wheel 66 or out of contact therewith. The pawl handle 69 is provided with a tooth portion 70 adapted to engage the teeth of the ratchet wheel before the dead-center position of the crank-frames and door links is reached to check the backlash of the ratchet wheel 66 during the initial door opening movement of the operating shaft.

The operating shaft is provided with square ends to facilitate operation from either side of the car by means of a removable lever (not shown). The pawl shaft 68 is equipped with an additional counterbalance and operating handle 71 fixed to the shaft whereby the ratchet pawl 67 and pawl handle 69 may also be actuated from the side opposite to the transmission side of the car. Both operating and pawl shafts are mounted for rotation in bearing brackets 72 and 73 secured to the side sills and at their intermediate portions in a bracket 74 secured to one of the draft members 32 of the underframe 9.

Assuming the doors to be in the locked raised position shown in Figs. 1 to 4 inclusive, the doors are released to drop the lading by first rotating the pawl shaft 68 by means of either counterbalance handles 69 or 71 to disengage pawl 67 from the ratchet wheel 66 and cause the tooth portion 70 of the handle 69 to engage the ratchet as indicated at the right hand side of Fig. 1. The operating shaft 53 being thus released for rotation the shaft is rotated by means of a lever fitted over a square end thereof. The rotation of the shaft is in the direction of the center of the car causing the lower portion of the link belt 54 to rotate the sprockets 52 and 51 in relatively opposite directions and away from the hopper end floors as indicated by the arrows in Figs. 6 and 7, respectively.

Prior to the beginning of sprocket movement the crank shafts 43 are locked against rotation by means of the lugs 50 of the sprockets bearing against the lugs 49 of the shafts as shown in Figs. 10 and 11. Upon rotation of the sprockets in opposite direc-

tions, as above described, the lugs 50 on the sprockets first move away from one side of the temporarily stationary crank shaft lugs 49 to the opposite side of said lugs as shown in Figs. 6 and 7. During this movement the sprockets will have rotated idly upon the temporarily stationary crank shafts under the influence of the link belt movement and the crank shafts released to permit rotation thereof.

Continued rotation of the sprockets in the direction indicated by the arrows in Figs. 6 and 7 will cause their respective crank shafts to rotate in the direction indicated by the arrows in Figs. 8 and 9. During this movement the driving force of the sprocket lugs 50 against the lugs 49 on the crank shaft will have carried the crank frames 26 past their dead-center positions on the shafts after which gravity will operate to cause said crank frames to yield to the weight of the supported load and move to the released position indicated in broken lines in Fig. 4 whereupon the doors will drop to the broken line position indicated in Figs. 1 and 3.

Immediately upon movement of the crank shaft under the influence of the downwardly moving doors, no further manipulation of the operating mechanism will be necessary, the sprockets remaining stationary from the inception of such movement to its consummation. During this period of rotation of the crank shafts in the direction indicated by the arrows in Figs. 8 and 9 the lugs 49 thereon will race away from the lugs 50 on the relatively stationary sprockets until they assume the position shown in said figures, as the doors drop to discharge the lading.

To raise the doors, the counter-balance handles 69 and 71 are thrown from their unlocking position shown in dotted lines in Fig. 1 to their initial ratchet locking position shown in full lines in that figure. This movement rotates the pawl shaft 68 and carries the ratchet pawl into engagement with the ratchet wheel 66 to lock the operating shaft against rotation in the opposite direction during the door raising operation. The operating shaft 53 is then rotated in a direction away from the hopper to effect a reverse movement of the link belt 54 causing rotation of the sprockets in the direction indicated by the arrows in Figs. 10 and 11. Continuing thus to rotate the operating shaft 53 will cause the sprocket lugs 50 to exert a driving force against lugs 49 on the crank shaft causing the crank shafts to rotate to return the crank frames 26 and the doors to their raised and locked position as shown in Figs. 1, 3 and 4.

It will be noted that to effect the relatively opposite movement of the crank shafts 43, one of said shafts, preferably the one adjacent the operating shaft 53, is arranged

outside of the link belt area. Instead of embracing the sprocket 51 and respective shaft 43 as in the case of sprocket 52 with respective shaft 43 at the opposite end of the transmission, the belt 54 is deflected from its course adjacent the sprocket 51 and directed to the upper peripheral side of said sprocket 51 and held and guided thereon by means of the idler 56 before mentioned.

10 The inner pairs of wheels 8 of the supporting trucks are shielded from the discharging lading by a pair of baffle plates 7^a secured adjacent the discharge opening 11 to the sloping end floor sheets 14 and to the 15 inner longitudinal side sill members 19.

The side walls of the car body are braced against bulging by a structure including the inside stiffeners 7 supplementing the framing gusset braces 62 and the top chords 6 20 surmounting the side wall plates 5. The top chords are of a general triangular configuration with a vertical side portion 4 secured to the outer face of the side wall plates and an inclined portion 3 extending downwardly and inwardly from said vertical portion, the vertical and inclined portions being connected together and to the adjacent side wall plate 5 by a horizontal base plate portion 2 provided with a marginal flange 1 25 lying against the inner face of the side wall and there secured by rivets 80 to the adjacent wall plate and vertical side 4 of said chord and to the inside stiffeners 7 as shown in Fig. 3. Thus arranged, the gusset 30 braces 62, inside vertical stiffeners 7, and top chords 6, with the hopper side sheets 13 and side wall plates 5 connecting them, provide a rigid structure within the lines of maximum width of the car to prevent 35 distortion of the car body under impact of the lading dropped from the loading buckets or from contact with the buckets themselves 40 during the loading operation, and against the racking stresses of draft and buffing 45 service.

What I claim is:

1. A hopper car having a single discharge opening, a pair of drop doors closing said opening and hinged longitudinally of the car, crank shafts mounted at opposite ends of the discharge opening and connected to the doors, an operating shaft, sprockets on said crank and operating shafts, a continuous chain power transmission connecting 50 all of said sprockets and loose connections between said crank shafts and their respective sprockets.

2. A hopper car having a single discharge opening and a pair of longitudinally arranged drop doors hinged at the car side and closing said opening, crank shafts arranged transversely of the car adjacent the opposite ends of said opening and connected to the doors, an operating shaft adjacent one of 60 said crank shafts, and transmission mecha-

nism connecting said operating shaft and one of said crank shafts and means adjacent the other of said crank shafts to hold said transmission mechanism in operative relation thereto whereby relatively opposite 70 rotation of said crank shafts is effected.

3. A door operating mechanism for hopper car doors arranged longitudinally of the car and including a pair of transversely extending crank shafts adjacent the opposite ends of said doors, an operating shaft, loose connection devices on said crank shafts, transmission mechanism connecting said crank and operating shafts through the medium of said loose connection devices, and 75 means adjacent one of said crank shafts to hold said transmission mechanism in operative relation thereto whereby relatively opposite rotation of said crank shafts is effected. 80

4. In a door operating mechanism for drop doors, crank shafts connected to the free edges of said doors, an operating shaft, transmission mechanism connecting said crank and operating shafts, loose connecting devices between said transmission mechanism and said crank shafts, and means intermediate said crank shafts to hold said transmission mechanism in operative relation to one of said crank shafts whereby relatively 85 opposite rotation of said crank shafts is effected.

5. In a door operating mechanism for cars having a pair of longitudinally arranged drop doors adapted to drop away from each other, crank shafts adjacent the ends of the doors and extending transversely of the car, an operating shaft, link belt mechanism connecting all of said shafts and loose connection devices between said link belt mechanism and said crank shafts. 100

6. In a door operating mechanism for drop doors, crank shafts connected to the free edges of said doors, an operating shaft, link belt mechanism connecting said crank 105 and operating shafts, loose connection devices between said link belt mechanism and said crank shafts, and means adjacent one of said crank shafts for effecting relatively opposite rotation of said crank shafts. 110

7. A hopper car having a single discharge opening and a pair of longitudinally arranged drop doors hinged at the car side, transversely extending crank shafts adjacent the opposite ends of said doors, an operating shaft, loose connection devices on said crank shafts to permit limited rotation of said crank shafts independently of the operating shaft, transmission mechanism connecting said operating shaft and one of 120 said crank shafts, and means adjacent the other of said crank shaft to hold said transmission mechanism in operative relation thereto for effecting relatively opposite rotation of said crank shafts. 125

8. A hopper car having a single discharge opening and a pair of longitudinally arranged drop doors hinged at the car side, transversely extending crank shafts adjacent the opposite ends of said doors, an operating shaft, transmission mechanism connecting said operating and crank shafts, loose connection devices between said transmission mechanism and said crank shafts adapted to effect simultaneous rotation of said crank and operating shafts, and means adjacent one of said crank shafts engaging said transmission mechanism with said crank shaft whereby relatively opposite rotation of said crank shafts is effected. 10
9. In a hopper car having hopper side and sloping end floor sheets defining a single discharge opening and a supporting underframe, a pair of longitudinally arranged doors closing said opening, brackets connecting the sloping end floor sheets and underframe and provided with inwardly extending trunnion bearings open at their tops, crank arms having integral trunnions mounted for rotation in said bearings, and bushings securing said crank arms in said bearings, said crank arms having supporting connection with said doors. 20
10. The combination with the drop doors of a hopper car having a single discharge opening and a supporting underframe, of brackets supported on the underframe adjacent the ends of said opening and provided with inwardly extending trunnion bearings open at their tops and fitted with removable bushings, crank arms having integral trunnions mounted for rotation in said bearings, said bushings being adapted to receive said trunnions over their peripheries. 30
11. In a door operating mechanism for cars having a pair of longitudinally arranged drop doors, crank arms connected to opposite ends of said doors and mounted for rotation to raise and lower the doors, crank shafts extending transversely of the car and having operative engagement with the respective crank arms, loose connection devices on said crank shafts permitting limited independent rotation of said shafts, an operating shaft, flexible transmission mechanism connecting said loose connection devices and through them the crank shafts and means holding said transmission mechanism in operative relation with one of said loose connection devices whereby relatively opposite rotation of the crank shafts is effected. 40
12. In a dumping car having a single discharge opening and a pair of longitudinally arranged doors closing said opening, a pair of oppositely rotatable crank shafts connected to said doors adjacent the opposite ends of said opening, a continuous operating means connecting said shafts having upper and lower strands and means engaging one of said strands of said operating
- means adjacent one of said crank shafts for effecting relatively opposite rotation of said shafts. 50
13. In a dumping car having a pair of longitudinally arranged drop doors and mechanism for operating said doors including a pair of transversely arranged crank shafts adjacent the opposite ends of said doors, shaft rotating sprockets loosely mounted thereon, a continuous connection for said sprockets having upper and lower strand portions, and means engaging the lower strand of said connection adjacent one of said sprockets permitting deflection of said lower strand to engage the upper peripheral side of said sprocket for effecting relatively opposite rotation of said crank shafts. 60
14. In a dumping car having a pair of longitudinally arranged drop doors and mechanism for operating said doors including a pair of transversely arranged crank shafts adjacent the opposite ends of said doors, shaft rotating sprockets loosely mounted thereon, a continuous connection for said sprockets having upper and lower strand portions, an idle roller above the lower strand of said connection adjacent one of said sprockets for deflecting said lower strand to the upper peripheral side of said sprocket for effecting relatively opposite rotation of said crank shafts and an operating shaft having a sprocket engaging said continuous connection. 70
15. In a dumping car having a pair of longitudinally arranged drop doors and mechanism for operating said doors including a pair of transversely extending crank shafts adjacent the opposite ends of said doors, an operating shaft adjacent to one of said crank shafts and fitted with a driving sprocket fixed to one end thereof, shaft rotating sprockets loosely mounted on said crank shafts, a continuous connection for said sprockets and operating shaft having upper and lower strand portions, and an idler above the lower strand of said connection adjacent one of said sprockets for deflecting said lower strand to the upper peripheral side of said sprocket for effecting relatively opposite rotation of said crank shafts, the upper strand of said connection having direct uninterrupted engagement with the driving sprocket on said operating shaft. 80
16. In a dumping car having a pair of longitudinally arranged drop doors and mechanism for operating said doors including a pair of transversely extending crank shafts adjacent the opposite ends of said doors, shaft rotating sprockets loosely mounted on said crank shafts, a continuous connection for said sprockets having upper and lower strand portions, an idler above the lower strand of said connection adja- 90

- cent one of said sprockets for deflecting said lower strand to the upper peripheral side of said sprocket for effecting relatively opposite rotation of said crank shafts and an 5 operating shaft having a driving sprocket fixed to one end thereof, the upper strand portion of said connection providing direct and uninterrupted engagement between the driving sprocket on the operating shaft and 10 the sprocket on the other of the crank shafts, said crank shafts being adapted to rotate independently of said operating shaft.
17. In a door operating mechanism for cars, a pair of crank shafts extending transversely of the car and connected for simultaneous operation, an operating shaft having a ratchet wheel fixed thereon operatively connected to said crank shafts, and a locking shaft having ratchet pawl mechanism arranged to engage said ratchet wheel to lock said operating shaft against reverse rotation during the door raising operation, said locking pawl having a handle portion provided with a ratchet engaging tooth for 25 checking the reverse rotation of the operating shaft during the initial door releasing movement of the operating shaft.
18. A car having a discharge opening, doors for said opening, crank shafts operatively connected to said doors, an operating shaft, sprockets on each of said shafts and a single transmission mechanism connecting all of said sprockets, said sprockets permitting movement of said crank shafts independently of said operating shaft.
19. A car having a discharge opening, doors for said opening, crank shafts for operating said doors, an operating shaft, sprockets on said shafts, a continuous power 40 transmitting means connecting all of said sprockets and means cooperating with the sprocket on said operating shaft to hold said power transmission means in engagement with one of said sprockets.
- 45 20. In a dumping car, an underframe, dumping doors, brackets mounted on said underframe and having trunnion bearings open at their tops, crank arms for operating said doors having trunnions rotatably mounted in said bearings and bushings be-

tween said trunnions and bearings retaining said trunnions in position.

21. A car having a discharge opening, doors for said opening, crank shafts for operating said doors, an operating shaft, 55 sprockets on said shafts and a continuous power transmitting means connecting all of said sprockets and operating said crank shafts in opposite directions.

22. A car having a discharge opening, 60 doors for said opening, crank shafts for operating said doors, an operating shaft, sprockets on said shafts and power transmitting means connecting said sprockets, said crank shafts and sprockets having a 65 loose connection permitting movement of said crank shafts independently of said operating shaft.

23. In a car, door operating crank shafts, an operating shaft operatively connected to 70 said crank shafts and having a ratchet wheel fixed thereon, a locking pawl for said ratchet wheel to prevent rotation of said operating shaft in one direction and an operating handle for said pawl, said handle being operable to engage said ratchet wheel to prevent rotation of said operating shaft in the opposite direction.

24. A hopper car having a discharge opening, drop doors closing said opening, 80 crank shafts connected to said doors, an operating shaft, a sprocket on each of said shafts, a chain power transmission engaging all of said sprockets and a loose connection between each crank shaft and its sprocket. 85

25. In a door operating mechanism for drop doors, crank shafts connected to the free edges of said doors, an operating shaft, sprockets on said crank and operating shafts, loose connection devices between said 90 crank shafts and their sprockets, a power transmission mechanism engaging all of said sprockets and means intermediate said crank shafts to hold said transmission mechanism in operative relation to one of said 95 sprockets, whereby relatively opposite rotation of said crank shafts is effected.

In witness whereof I have hereunto set my hand.

VICTOR WILLOUGHBY.
